UNITED STATES PATENT OFFICE.

OSCAR WERWATH, OF MILWAUKEE, WISCONSIN, ASSIGNOR TO KEWAUNEE MFG. CO., OF KEWAUNEE, WISCONSIN, A CORPORATION OF WISCONSIN.

CABINET.

1,271,641.

Specification of Letters Patent. Patented July 9, 1918.

Application filed January 22, 1918. Serial No. 213,238.

To all whom it may concern:

Be it known that I, OSCAR WERWATH, a citizen of the United States, and a resident of the city of Milwaukee, county of Milwaukee, and State of Wisconsin, have invented 5 certain new and useful Improvements in Cabinets, of which the following is a specification.

My invention relates to improvements in 10 cabinets especially designed for use in conducting electrical experiments in the teaching of electricity, and has for its object the provision of an improved construction of this character, capable of efficient and convenient use by a comparatively large number 15 of students.

The invention consists in the combinations and arrangements of parts hereinafter described and claimed.

20 The invention will be best understood by reference to the accompanying drawings, forming a part of this specification, and in which,

25 Figure 1 is a perspective view looking at one side of a cabinet embodying the invention,

Fig. 2, a vertical transverse section of the same,

30 Fig. 3, a perspective view of a modified form of construction, and

Fig. 4, a vertical transverse section of the construction shown in Fig. 3.

The form of construction illustrated in 35 Figs. 1 and 2, comprises a cabinet body 5 in the form of a table entirely open at both sides and provided with a transverse partition 6, dividing the same into upper and lower compartments. Channel guide members 8 are arranged at the top of the upper 40 and the bottom of the lower compartment and double transverse channel guides 9 are arranged in the partition 6 between the compartments, said channel guides being arranged to coöperate together to constitute 45 guides for a plurality of mounting bases or ports 10 and to permit of the ready removal or insertion of said bases from either side of the cabinet. The various bases 10 are equipped with various simple forms of electrical 50 appliances, such as various forms of push buttons, switches, bells, buzzers, lights, etc., for performing the various electrical experiments in the course of instructions in electricity. The table top 5 is also equipped

with foldable extension leaves 11, hinged to 55 the sides thereof and adapted to be folded downwardly or extended as indicated to increase the available top surface of the table top.

A supporting standard 12 is arranged centrally over the table top 5 and extends substantially the full length thereof. This standard is equipped with a number of transverse openings 13 therein, adapted to receive the bases 10, and bases 10 are provided at 60 their edges with flanges 14 adapted to fit against the outer faces of the standard 12. Buttons or swinging latches 15 are provided on standard 12 in position to engage over the flanges at the tops of bases 10 to secure said 65 bases in place. A number of electrical terminals 16 are arranged across the top of each side of standard 12, and are suitably connected with electrical supply wires, to furnish electrical current of various characters, 70 such as direct and alternating current and both of different voltages or potentials. Suitably marked plates 17 are arranged under the terminals 16 so as to permit of the ready identification of the same for ready 75 reference.

By this arrangement it will be observed that the various mounting bases 10 may be kept in the table body 5, ready for use, and available from either side of the table, thus 80 permitting of one or more students to experiment at each side of the table with the full equipment of the cabinet available for use.

The form of construction illustrated in 85 Figs. 3 and 4 of the drawings is the same as that already described, except that the upper standard in this instance is itself provided with upper and lower cabinet compartments 18 and 19, extending entirely 90 therethrough and equipped on each side with sliding glass doors, giving access thereto from each side. Flanges 21 are arranged on the standard to extend outwardly beyond the doors 20 and are proportioned to receive 95 the bases 10 with the flanges 14 resting against the outer edges of flanges 21, and buttons 15 are provided for securing the bases in place. By this arrangement it will 100 be seen that different forms of appliances may be kept in the cabinet compartments 18 and 19, and are equally available for use 105 from each side of the cabinet. Otherwise

the construction and operation is the same as that already described.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims:

Having described my invention what I claim as new and desire to secure by Letters 15 Patent is:

1. A cabinet body having a compartment therein extending transversely therethrough; a standard on top of said body, having releasable mountings on each side, 20 and interchangeable mounting bases insertible in said compartment or in said mountings, substantially as described.

2. A cabinet body having a compartment therein extending transversely therethrough, said compartment being open at and accessible from both sides of the cabinet; transverse guides extending entirely 25 through said compartment and arranged to permit of the removal or insertion of articles from both sides; a standard on top of said body having releasable mountings on each side; and interchangeable mounting bases insertible in the guides in said compartments or in said mountings, substantially 30 as described.

3. A cabinet body having a compartment therein extending transversely therethrough, said compartment being open at and accessible from both sides of the cabinet; a standard on top of said body having releasable mountings on each side; electric 40 terminals of various characters on each side of said standard; and interchangeable mounting bases insertible in said compartments or in said mountings, substantially 45 as described.

4. A cabinet body having a compartment therein extending transversely therethrough, said compartment being open at and accessible 50 from both sides of the cabinet; transverse guides extending entirely through said compartment and arranged to permit of the removal or insertion of articles from both sides; a standard on top of said body having releasable mountings on each side; electric 55 terminals of various characters on each side of said standard; and interchangeable mounting bases insertible in the guides in said compartments or in said mountings, substantially 60 as described.

5. A cabinet comprising a body having a compartment therein extending transversely therethrough, said compartment being open at and accessible from both sides of the 65 cabinet; a standard on top of said body,

said standard having openings extending transversely therethrough; interchangeable mounting bases insertible in said compartments or in the openings in said standard, said bases having flanges around their edges 70 contacting with the outer faces of said standard; and buttons on said standard arranged to engage over the flanges at the upper edges of said bases, substantially as described.

6. A cabinet comprising a body having a compartment therein extending transversely therethrough, said compartment being open at and accessible from both sides of the cabinet; transverse guides extending through 80 said compartment and arranged to permit the insertion or removal of articles from each side; a standard on top of said body, said standard having openings extending transversely therethrough; interchangeable mounting bases insertible in the guides in said compartments or in the openings in said standard, said bases having flanges around their edges contacting with the outer faces of said standard; and buttons 85 on said standard arranged to engage over the flanges at the upper edges of said bases, substantially as described.

7. A cabinet comprising a body having a compartment therein extending transversely therethrough, said compartment being open at and accessible from both sides of the cabinet; a standard on top of said body, said standard having openings extending transversely therethrough; interchangeable mounting 90 bases insertible in said compartments or in the openings in said standard, said bases having flanges around their edges contacting with the outer faces of said standard; electric terminals of various characters on 95 each side of said standard; and buttons on said standard arranged to engage over the flanges at the upper edges of said bases, substantially as described.

8. A cabinet comprising a body having a compartment therein extending transversely therethrough, said compartment being open at and accessible from both sides of the cabinet; transverse guides extending through 110 said compartment and arranged to permit the insertion or removal of articles from each side; a standard on top of said body, said standard having openings extending transversely therethrough; interchangeable mounting bases insertible in the guides in 115 said compartments or in the openings in said standard, said bases having flanges around their edges contacting with the outer faces of said standard; electric terminals on each side of said standard; and buttons on said standard arranged to engage over the flanges at the upper edges of said bases, substantially 120 as described.

9. A cabinet comprising a body portion; a standard on top of said body portion, said 130

standard being provided with one or more cabinet compartments extending entirely therethrough; and doors at each side of the compartments of said standard, substantially as described.

10. A cabinet comprising a body portion; a standard on top of said body portion, said standard being provided with one or more cabinet compartments extending entirely therethrough; doors at each side of the compartments of said standard; supporting flanges extending laterally above and below said doors; and buttons coöperating with said upper flanges, substantially as described.

11. A cabinet comprising a body portion; a standard on top of said body portion, said standard being provided with one or more cabinet compartments extending entirely therethrough; doors at each side of the compartments of said standard; and electric ter-

minals of various characters at each side of said standard, substantially as described.

12. A cabinet comprising a body portion; a standard on top of said body portion, said standard being provided with one or more cabinet compartments extending entirely therethrough; doors at each side of the compartments of said standard; supporting flanges extending laterally above and below said doors; buttons coöperating with said upper flanges; and electric terminals of various characters at each side of said standard, substantially as described.

In testimony whereof I have signed my name to this specification in the presence of two subscribing witnesses.

OSCAR WERWATH.
